HIGH TEMPERATURE TORCH

Alexander Rava, Chicago, Ill.

Application May 15, 1933, Serial No. 671,150

4 Claims. (Cl. 91—12.2)

This invention relates to methods and means for producing high temperature flames.

Although my invention has numerous applications, it is particularly applicable to the production of non-reducing flames in the chemical, ceramic and other allied arts. An illustrative use is the fusing and melting of refractory material and/or the glazing of the same and/or the depositing thereon of a layer or layers of glazing material, metals etc.

It is an object of my invention to provide an improved method and means for producing a high temperature flame.

Another object is to provide a method and means for producing a high temperature flame in a unitary torch or like construction.

Another object is to provide an improved method and means for producing a high temperature oxidizing or non-reducing flame.

Another object is to provide an improved method and means for producing a high temperature flame by which refractory material may be fused and/or melted and/or glazed without the introduction thereinto of impurities.

Another object is to provide an improved method and means for applying a layer of glaze or the like to refractory or like materials.

Another object is to provide an improved method and means for heating and applying to a refractory or like surface a layer of glaze substantially without the introduction of impurities thereinto.

Another object is to provide a method and means for producing a high temperature flame by the combustion of a metal or metals in the presence of a combustible gas or gases.

Another object is to provide a method and means for utilizing the high combustion temperature of a metal or metals in the production of a high temperature flame.

Another object is to provide a method and means for increasing the combustion temperature of two or more gases to increase the temperature of the flame of combustion thereof.

Another object is to provide a method and means for producing a high temperature flame by the concurrent combustion of a gas or gases and a solid such as a metal or a mixture of metals.

Other objects will be apparent to those skilled in the art to which my invention appertains.

My invention is fully disclosed in the following description taken in connection with the accompanying drawing, which illustrates a flame producing burner embodying my invention, and by

which the method of my invention may be practiced.

Referring to the drawing, I have shown at 1 the main body of the burner. It comprises an inner cup-form wall 2 upwardly open and upwardly outwardly flaring and providing a generally frustoconical open chamber 22; and an outer wall 3 which may be of cylindrical form; thus providing, between the walls 2 and 3, a space or chamber 4. Conduits 5 and 6 communicate with the interior chamber 4 and provide means, whereby a cooling medium, such as water or air under pressure, may flow to conduct away from the body 1 heat accumulating therein in the operation of the device or torch to be described.

A plurality such as six passageways 7 extend entirely through the two walls, 2 and 3, being sealed thereto by tubular connecting portions 8—8, and burners 9—9 and 10 are projected through the passageways 7. Each of the burners 9 comprises a nozzle 11 having a discharge orifice 12 and a jacket 13 surrounding the same, providing a space 14 between the jacket and the nozzle, through which a cooling medium, such as water or air, may be circulated to conduct away heat. The medium may be introduced into the jacket through a conduit 15 and after circulating therethrough may be discharged through a conduit 16. The nozzle 10 may be identical with the nozzle 9—9 and may have a discharge orifice 13 from its nozzle 11.

The burners 9—9 are disposed in an annular series with the axes of their nozzles 11, or of their orifices 12—12, inclined at an angle of approximately 75° (or less) to the axis of the frusto-conical chamber 22, and the orifices 12—12 are disposed substantially equal distances from the said axis and in a plane at right angles to the axis and substantially midway between the upper and lower bases of the said frusto-conical chamber.

The nozzle 17 of the burner 10, or the orifice 13 thereof, is disposed substantially along or on the said axis centrally of the said orifices 12 and substantially below the plane of the orifices 12—12.

The nozzles 11—11 extend rearwardly out of the jacket 13 into conduit portions 18—18 which are adapted to be connected to a supply source of oxygen under pressure. Any suitable means may be provided, such as means well known in the art, for supplying oxygen to the nozzles 11—11 from such source and for controlling the pressure thereof and therefore the rate of flow to the nozzles. The nozzle 17 of the burner 10 is likewise provided with a conduit extension 19 adapted to

be connected to a source of hydrogen under pressure controlled by suitable means not shown.

In the operation of the torch or burner, thus far described, hydrogen is admitted to the burner 10 through the orifice 13 and ignited producing a flame jet 20. Oxygen is then admitted to the burner 9—9 and issuing from the orifices 12 combines with the hydrogen producing a flame 21 issuing from the burner upwardly along its central axis.

The supply of oxygen to the burners 9—9 then has introduced thereinto finely powdered zirconium metal. When the metal, with the oxygen issuing from the orifices 12—12, comes in contact with the central hydrogen flame jet 20, the intense heat of the oxy-hydrogen flame burns the zirconium metal to zirconium dioxide. As is well known, zirconium metal has a very high heat of combustion and its combustion in the torch just described, raises the temperature of the oxy-hydrogen flame producing an exceedingly intense heat.

The zirconium dioxide in the flame is highly sintered or molten and is projected forwardly in the flame 21 and may be deposited by the onrush of the hot gases from the flame on any desired surface. If desired, before the metal is introduced into the oxygen streams, the oxy-hydrogen flame alone may be employed to heat the article or surface upon which the zirconium dioxide is subsequently to be deposited.

As is apparent, zirconium dioxide as a refractory material is produced in the torch as just described, from zirconium metal and under conditions, which cause it to be chemically pure, the resulting flame being a non-reducing or oxidizing flame. By this means, as will also be apparent, a refractory article may be provided with a glazed surface.

40 As an alternative mode of operation, instead of introducing zirconium dust alone into the oxygen, it may be introduced together with magnesium metal dust or powder. The refractory material thus produced and/or the refractory glaze layer, which may thereby be applied to an article, will be a mixture of zirconium and magnesium oxides. A means for introducing the powdered metal into the oxygen streams has not been shown and is believed not to be necessary in view 50 of the state of this art, and any suitable or known means may be provided for this purpose.

My invention is not limited to the particular metal zirconium referred to nor to its combination with magnesium; other metals and other combinations may be used.

In some cases refractory oxide dust may be introduced into the flame with the gas or gases for depositing on a surface as described.

Other changes and modifications in the apparatus above described and changes and modifications may be made in the steps of process hereinbefore described without departing from the spirit of my invention or sacrificing its advantages, or departing from the scope of the appended claims.

I claim:

1. In a high temperature torch or the like, a frame having a generally cup-form combustion chamber, a jet flame gas burner projecting into the

chamber through the bottom thereof disposed to project a jet of flame through and out of said cup form combustion chamber, and a plurality of gas jet nozzles projecting laterally into the chamber through the side wall thereof and disposed around the central burner and projecting flame jets inwardly and outwardly to join with the first named flame jet. 5

2. In a high temperature torch or the like, a frame comprising a generally outwardly open cup-form walled combustion recess, a generally central jet burner nozzle projecting into the recess through the bottom wall thereof and terminating inwardly of the recess mouth and disposed to project a central jet of gas outwardly through the recess along the jet axis, a plurality of jet burner nozzles projected into the recess through side walls of the chamber terminating inwardly of the recess mouth and arranged in a series around the central nozzle substantially symmetrically thereto and disposed to project jets of gas toward the central jet from different angular directions each in an outwardly inclined direction, the axes of the series of jets substantially intersecting the axis of the central jet at a point therein, the 20 series of jets joining with the central jet to produce a flame projected outwardly of the recess along the axis of the central jet.

3. In a high temperature torch or the like a frame comprising a generally cup-form outwardly open walled combustion recess, a generally central hydrogen jet burner nozzle projecting into the recess through the bottom wall thereof terminating inwardly of the recess mouth and disposed to project a central jet of hydrogen 30 through and out of the recess, along a jet axis, a plurality of oxygen jet burner nozzles projected into the recess through side walls thereof terminating inwardly of the recess mouth and arranged generally symmetrically around the central nozzle and disposed to project jets of oxygen towards the hydrogen jet from different angular directions each in an outwardly inclined direction, the axes of the oxygen jets substantially intersecting the axis of the hydrogen jet at a 45 point therein whereby the oxygen jets may join with the hydrogen jet to produce a non-reducing flame projected outwardly of the recess along the axis of the hydrogen jet.

4. In a high temperature torch or the like, a frame comprising a generally outwardly open cup-form walled combustion recess, a generally central jet burner nozzle projecting into the recess through the bottom wall thereof and terminating inwardly of the recess mouth and disposed to project a central jet of gas outwardly through the recess along the jet axis, a plurality of jet burner nozzles projected into the recess through side walls of the chamber terminating inwardly of the recess mouth and arranged in a 60 series around the central nozzle substantially symmetrically thereto and disposed to project jets of gas toward the central jet from different angular directions each in an outwardly inclined direction, the series of jets joining with the central jet to produce a flame projected outwardly of the recess along the axis of the central jet. 65
